MERCURY SAFETY SWITCH

Stanley R. Matthews and Thomas J. Darlington,
Winston Salem, N. C.

Application January 5, 1948, Serial No. 552

2 Claims. (Cl. 200—152)

1

The invention relates to mercury switches and more particularly to a mercury type switch which is adapted to be applied to a road vehicle.

The main object of the invention is to provide a mercury or liquid type switch comprising two half members which are adapted to be bolted together, the half members embodying electrical terminals, the terminals communicating with a cavity which is normally filled with, or contains mercury, whereby contact is made between the respective terminals.

Another object of the invention is to provide a switch of a type-mentioned, which, in the event that the switch is turned or tilted, the mercury will leave the cavity and break the contact between the respective terminals.

Another object of the invention is to so fasten the inner surfaces of the respective plates of the switch whereby, when the switch is once turned and the mercury leaves the cavity it cannot again be returned to the cavity other than by manual means.

The switch is particularly adapted for use on road vehicles and especially trucks or tractors which, in the case of an accident or the overturning of the vehicle the entire electrical system of the vehicle will be disrupted and connection cannot again be made other than by manual operation.

The invention is illustrated in the accompanying drawings in which:

Fig. 1 is a top plan view of the switch showing one terminal thereof being connected to a battery post and the other to a terminal communicating with the electrical system;

Fig. 2 is a side elevation;

Fig. 3 is an end view looking at the switch from the right hand side;

Fig. 4 is an inside view of one of the halves of the switch;

Fig. 5 is an inside view of the other half of the switch, and

Fig. 6 is a section through the switch.

Referring more specifically to the drawing in which like numerals indicate similar parts throughout the various views the switch is shown generally at 6 and comprises two members 7 and 8, made entirely of an insulating material such as fiber, the member 7 having a flanged terminal 9 fastened thereto as by bolts 10 and terminating in a clamp portion 11, said clamp portion being adapted to be attached to a terminal post 12 of a battery 13. The other half of the switch 8 has attached thereto a flanged portion 14 terminating in a member 15 which is adapted to be engaged by

a clamp 16 of a cable terminal 18. As will be seen the respective terminals 11 and 15 are held in closed relation as by the bolts 10 and the nuts 19 threaded thereon. Referring specifically to Figure 4 the plate or portion 7 has a mercury cavity 20, the same having connected thereto spillways 21, spillways leading to and cooperating with a trap portion 22. Figure 5 discloses the inner construction of the portion 8 of the switch the same embodying a recessed or mercury cavity 23 and recesses 24. Member 7 further has at the uppermost end a fill opening and passage 25 closed as by screw 26. At its lower side the race or trap 22 communicates with the main opening 27 closed by screw 28. The respective terminals 9 and 14 have rubber or like washers 29 spaced therebetween at that portion where they join the side of the casing to prevent leakage of the mercury.

In its assembled condition it will readily be seen that the recesses 20 and 23 are in alignment and that the passages 24 permit a passageway to the spillways 21 in the event or during the turning or inversion of the switch, whereby mercury or other liquid will run through the passages into the trap or waste 22.

In the operation of the switch the same is normally placed in connection with one post of a battery at one side and to the electric cable at the other side, and in its normal position the recesses 20—23 are normally filled with mercury or the like, so that when the switch is in its upright position as shown in Figures 1 and 2 the mercury is trapped in the recesses and thereby it makes contact between the terminals 9 and 14. In the event that the vehicle to which the switch is attached is overturned the mercury passes from the recesses through the spillways 21 into the trap chamber 22. Once the mercury is in this trap chamber it cannot in any way be returned to its former position in the recesses 20—23, even though the vehicle should turn over several times and right itself, the mercury would still be trapped in the raceway 22. Under these conditions in order to make electrical contact and resume or complete the electrical system it would be necessary to withdraw the drain plug 28 and drain the mercury out, after which, the plug could be replaced and the mercury inserted through the passage 25 upon removing of the screw 26.

It will thus be seen that we have devised a very advantageous switch, mainly because, in the event that the same is once turned the liquid cannot return to make the necessary electrical

contact until the same is manually done. Thus in the event of an accident it would be impossible for an automobile or other vehicle to be in an accident and turn over and then right itself and automatically have the electrical system reconnected. Thus it will readily be seen that such a switch is an absolute precaution against the possibility of fire in the event that an automobile is turned over because the entire electrical system is disconnected and therefore there can be no sparking which is a main source of fire hazard when a vehicle is overturned.

The invention is not limited to the exact construction shown but may be varied within the scope of the following claims.

We claim:

1. A safety mercury type switch comprising in combination two terminal members and a body of insulating material, said body member consisting of two half members, each half member having a central bore therethrough, said bores forming a mercury receiving recess when the half members are placed face to face, one of each of the two terminal members having a surface lying flush with the outer surfaces of the half members and overlying the mercury recess, the inner face of one of the half members having an annular trap chamber therein and radially disposed spillways communicating with the trap chamber at their outer ends and having their inner ends in communication with the mercury recess, said half member further having a radially disposed filling passage extending inwardly from the outer edge of the member and communicating at its inner end with the mercury recess and a mercury drain passage extending through the lower wall of the half member and opening in the annular recess.

2. A safety mercury switch comprising in combination two terminal members and a body mem-

ber of insulating material, said body member consisting of two half members, one of each of the terminals connected with the outer face portion of each half member, each of the half members having a recess bored through their center portions and adapted to align when the half members are placed face to face and thereby form a mercury recess, the terminal members having portions overlying the mercury recess, the inner face part of one of the half members having formed therein an annular trap channel and spaced apart spillways in communication at their outer ends with the annular trap channel and radiating inwardly and communicating at their inner ends with the mercury recess, a mercury drain opening extending through a wall of the half members, and a mercury refill opening extending laterally through the wall of the half member and terminating at its inner end in communication with the mercury recess, and bolt and nut means extending through the respective half members and terminal members to hold the switch in assembled relation.
